HONE

Jake Manfred Stivers, Carthage, Mo.

Application May 3, 1934, Serial No. 723,672

11 Claims. (Cl. 51—211)

The present invention relates to hones and more particularly to a novel hone which is adapted to be held in the hand when used and which will provide a sharp, even edge for the tool or instrument with which it is used.

The chief defect with the hand hones of the prior art was that they would not give an even edge to the tool no matter how careful the operator was. In sharpening a razor, knife or other tool thereon the operator could not apply a perfectly even pressure on the entire surface of the edge contacting the stone and which was being sharpened. While this is true of all hones it is especially so in regard to hones that are held in one hand while the tool to be sharpened is held in the other. In such cases there is a tendency to hold the hone unevenly and also to apply too much pressure on one side or the other of the edge. Such sharpening not only gives an uneven edge to the blade but causes it to wear out much sooner. The operator sharpens one portion more than another then must even up the rest with the result that he uses the hone more than necessary and more than he would if the blade were sharpened evenly.

It is therefore, an object of my invention to provide a hone which will yield to pressure and remain even with the blade to be sharpened under all circumstances. I accomplish this by 30 rockably positioning my stone on a ridge in the holder. This ridge acts as a fulcrum and when too much pressure is applied to one side or the other of the stone it will rock on its support so as to assume the correct position in relation to the tool being sharpened.

Another object is to provide a holder for the stone which may be easily, securely and safely held in the hand without danger to the operator.

Another object is to provide a novel means for 40 rocking the stone in the holder which may also be adjusted to hold the stone against movement therein.

Another object is to provide a novel mounting for the stone within the holder and in which the stone may be quickly, easily and securely inserted.

Still another object is to provide a holder and stone therefor which may be readily assembled and disassembled to replace the stone or for other 50 purposes.

Further objects are to provide a construction of maximum simplicity, efficiency, economy and ease of assembly, and such further objects, advantages and capabilities as will later more fully appear and as are inherently possessed thereby.

The invention further resides in the combination, construction and arrangement of parts illustrated in the accompanying drawing, and while there is shown therein a preferred embodiment, it is to be understood that the same is 5 susceptible of modification and change, and comprehends other details and constructions without departing from the spirit of the invention.

In the drawing:

Fig. 1 is a view in perspective of my holder with the hone secured therein but with the top removed.

Fig. 2 is a longitudinal cross section through the center of the hone and holder.

Fig. 3 is a lateral cross section on the line 3—3 of Fig. 2.

Fig. 4 is a view similar to Fig. 3 but with the nut in the base of the holder loosened to enable the hone to be rocked.

Fig. 5 is a view of the hone partially removed from the mounting therefor.

Referring more particularly to the drawing disclosing my preferred embodiment, 1 represents my holder and 2 the top therefor. The 25 holder is a receptacle of wood or other suitable material having sides 3, ends 4 and 5 and base support or bottom 6. This base may have a flat or other shaped lower surface 7 but the upper or inner surface 8 is provided with a ridge 9. The 30 base is also provided with a hole 10 having upwardly tapering sides 11. This hole is preferably in the center of the base.

The hone 12 is provided with a mounting 13 having projections 14 and 15 and bolt 16 attached 35 to the under side thereof in any desired manner. This bolt is adapted to protrude through the hole 10 of the base 6 and is provided with a nut 17 the upper portion of which 18 has sides which slope at the same angle as the sides 11 of the 40 hole 10. The lower portion 19 of this nut is knurled to facilitate turning the same.

The end 4 of the holder is provided with a depression 20 to receive the projection 14 of the mounting. The end 5 is provided with a threaded hole 21 adapted to receive a screw 22 having a depression 23 at the inner end thereof. The projection 15 of the mounting is received in this hole 21. When the screw 22 is inserted therein the projection 15 enters the depression 23 and 50 is held against longitudinal movement thereby.

It will be noted that the projection 15 is longer than the projection 14. When the mounting is pushed so that the projection 14 contacts the inner end of the depression 20 it is impossible 55

to remove the hone and mounting. However, 5 should the screw 22 be removed and the mounting moved toward the hole 21 the projection 15 may penetrate some distance therein, releasing the projection 14 from its depression 20 and, after the nut 17 has been removed, permitting withdrawal of the hone and mounting from the holder.

The mounting 13 may be of any suitable material and is provided, preferably integrally with resilient flanges 24 and 25 which are bent slightly inwardly. The hone is pushed into the mounting from either end, see Fig. 5, and is gripped by these flanges whereby to substantially prevent 15 any movement thereof either laterally or vertically although yielding to longitudinal pressure.

The projections 14 and 15 are substantially in 20 the middle of the ends of the mounting and the depression 20 and hole 21 are in the middle of the ends 4 and 5 of the holder and just above or even with the ridge 9 of the base 6. When the mounting is inserted into the holder as above described it will therefore seat on this ridge. When the nut 17 is screwed onto the bolt 16 until 25 the sides of the nut come into full contact with the sides 11 of the hole 10, the mounting will be securely anchored or held against any movement and will remain stationary on this ridge. See Fig. 3.

30 However, when the nut 17 is loosened as in Fig. 4, the mounting and hone will yield to pressure on either side thereof and will rock on the ridge 9. It is used in this manner, the advantages of which have been explained above. When 35 the tool to be sharpened is applied to the hone it will rock on its base so as to be even or parallel with the edge of the tool applied thereto. The hone is prevented from longitudinal or vertical movement by the projections 14 and 15 being firmly secured in the ends of the holder by the screw 22.

The sides of the holder are provided near the bottom thereof with bulges or protuberances 26 which provide a means for grasping or holding 45 the device without danger of the tool being sharpened coming into contact with the hand of the operator.

Having thus disclosed my invention,

I claim:

50 1. In combination, a hone, a holder therefor, comprising a receptacle having a ridged inner bottom, and means for holding said hone on said ridge either rockably or stationary as desired.

55 2. In combination, a hone, a holder therefor, comprising a receptacle having a ridge on the inner bottom thereof, said bottom having a tapered hole therein, a mounting for said hone, a bolt on the bottom of said mounting and extending through said hole, a tapered nut for said bolt and adapted when screwed tightly to hold said mounting and hone from movement on said bottom and, when said nut is loosened, to permit a lateral rocking of said hone.

60 3. In a hone holder, a hone, a mounting therefor, and means for removably securing said mounting in said holder, comprising an extension on each end of said mounting, a depression in one end of said holder, a threaded hole in the

opposite end, and a nut for said hole, said nut having a depression in one end thereof, said depressions receiving said extensions.

5 4. In combination, a hone, a holder therefor comprising a base for said hone, a ridge on the upper side of said base and upon which the hone is adapted to rest, and means for attaching said hone to said base.

10 5. In combination, a hone, a holder therefor comprising a four sided receptacle provided with a ridged base having a tapered hole therein, a bolt on said hone and adapted to extend through said hole, a tapered nut for said bolt and adapted to fill said hole whereby to anchor said stone to said base, and means for securing said hone to the ends of said receptacle.

15 6. In combination, a hone, a holder therefor having four sides and a base, means for rockably attaching said hone to said base, and means for attaching said hone to two sides of said receptacle.

20 7. In combination, a hone, a holder therefor having a ridged base and sides extending thereabove, a mounting for said hone, means on said mounting for rockably attaching it to said base, and means on said mounting for detachably securing it to said holder.

25 8. In combination, a hone holder, a hone, a mounting for the hone comprising a strip having resilient flanges whereby to grip the hone and prevent lateral movement thereof but permitting its longitudinal removal therefrom, extensions on each end of the strip for securing it to the sides of the holder and a projection on the bottom of the mounting for securing it to the base of the holder.

30 9. A hone, a holder therefor, a base for said holder having a hole in the center thereof, the upper side of said base having a ridge, said hole tapering upwardly, said hone holder having a 40 projection extending into said hole, and a tapered nut adapted to fit on said projection whereby to substantially fill said hole and hold said hone steady on said ridge, said nut when loosened permitting a rocking of said hone.

45 10. A hone, a holder therefor, a mounting for said hone, a base for said holder and on which said mounting rests, means for detachably and rockably supporting said mounting on said base, and means for removably attaching said mounting to the ends of said holder and comprising extensions on the ends of the mounting, one extension being longer than the other, a depression in one end of the holder for receiving said smaller extension, the other end being provided 55 with a threaded hole, a nut adapted to fill said hole, the inner end of said nut having a depression for receiving said longer extension whereby, when said nut is screwed into said hole, any longitudinal movement of said mounting is prevented.

60 11. In combination, a hone, a holder therefor, comprising a receptacle having a ridged inner bottom provided with a hole therethrough, a mounting for said hone, a bolt on the bottom of said mounting and adapted to extend through said opening, and a nut for said bolt.

JAKE MANFRED STIVERS.
